Claims priority, application Germany Apr. 5, 1956

13 Claims. (Cl. 95—94)

The present invention relates to an apparatus for and a method of handling and processing photographic material, particularly for the development of roll films. Development equipment is already in use in which the photographic material is moved through several tanks arranged one after another, by conveyor means comprising a horizontal and a vertical conveyor. A common container having partition walls houses the different tanks. The conveyor means either pass through these tanks or they are mounted on top of them, so that the space above the container is also completely filled out. Such an arrangement has various disadvantages. On the one hand, the different tanks cannot be exchanged or cleaned individually, and on the other hand, the conveyor means above the tank make it difficult to carry out necessary examinations or single and test developments. Furthermore, it is not possible to adjust the apparatus from black-and-white development which requires a few tanks only, to color development.

It is therefore, one object of the present invention to eliminate these deficiencies and to provide an apparatus which requires a minimum number of construction elements and smallest possible floor space, and at the same time renders highest possible output and allows for completely automatic handling of the photographic material to be processed. This is accomplished in such a manner that the elements, forming the conveyor means, are mounted on the rear side of and above the tanks and in that the tanks form individual separate containers, so that the front of the apparatus is easily accessible and the different containers are individually removable. Through means of suitable coupling devices on the vertical conveyor and co-operating coupling means on the material carriers, transfer of the material carriers from the horizontal conveyor to the vertical conveyor and vice versa is accomplished. The photographic material to be processed is attached to suitable carriers and stacked in a loading station at the front end of the apparatus. It is then automatically received by the conveyor means and passed through the different tanks at the required speed which is adjustable. At the end of the process, the material is stored in a delivery station at the end of the apparatus.

It is another object of the present invention to provide the vertical conveyor with controllable clamping devices for the material carriers and control members for said clamping devices are arranged at the points of transfer from the horizontal to the vertical conveyors and vice versa. For each horizontal conveyor several separate vertical conveyors may be provided comprising an endless chain having clamping devices and being arranged within the contours of the individual tanks.

It is yet another object of the present invention to form the vertical conveyor by a chain, which has pins; arranged with rotatable clamping devices, each of which has a reversible clamp which prevents the movement of the clamping device at least during the transport of the material. To control the compression members of the

2

clamping devices and the clamps, fixedly mounted control members, as for instance cams, stops, guides, or the like are provided on both sides of the chain forming the vertical conveyor. At the upper point of reversal of each vertical conveyor, a glide member is provided on a pivotable arm and receives the incoming clamping devices which by maintaining their vertical attitude are transferred to the downward moving strand of the conveyor.

With these and other objects in view which will become apparent in the following detailed description, the present invention will be clearly understood in connection with the accompanying drawings, in which:

Fig. 1 is a diagrammatic side elevation of the apparatus;

Fig. 2 is a top plan view thereof;

Fig. 3 is a section along the lines 3—3 of Figure 1; Figs. 4, 5, 6 and 7 are fragmentary views of different parts on an enlarged scale;

Fig. 8 is a diagrammatic illustration of a part of the tanks, of the horizontal and of the vertical conveyor;

Fig. 9 is a side elevation of another embodiment shown in Fig. 8, partly in section;

Fig. 10 is a front view of a clamping device provided on the vertical conveyor as used in the embodiment according to Fig. 8;

Fig. 11 is a side view of the clamping device immediately before receiving the material carrier;

Fig. 12 is a top plan view of the arrangement shown in Fig. 10; and

Fig. 13 is a diagrammatic illustration of the point of transfer of the material carrier from the horizontal to the vertical conveyor.

Referring now to the drawings and in particular to the embodiment disclosed in Figs. 1 to 7, individually replaceable tanks 1, 2, 3 and 4 are used. The tank 1 contains the developing agent, the tank 2 serves as a flushing basin having spray nozzles 34, the tank 3 is the fixing bath and the tank 4 is the washing container.

The horizontal conveyor is mounted immediately above the tanks 1, 2, 3 and 4, and comprises two transport chains 12, ropes, or the like which pass over guide rollers 13 and which are driven by a suitable power source at uniform speed. The horizontal conveyor brings about the movement of the material through the tanks. The vertical conveyor receives the material at the end of each tank to lift it out and to dip it into the following tank. This conveyor is formed of an endless transport chain 5 and arranged on the rear side of the tanks. The chain 5 is provided with catches 6 for the material carriers 7 and passes over guide wheels 14. It moves, at the points of transfer, up and down between the different tanks according to the length of the film to be developed.

The conveyors 5 and 12 are driven at any required speed by an electric motor 9 which, through a gear unit 11, also drives a fan 10 accommodated in the drying chamber 26. A wall 26a separates the gear unit and the drive means from the rest of the drying chamber 26.

The material carriers comprise substantially rods 7 which are bent at one end as at 8, to which the material 60 to be processed, as, for instance, a roll film 23, is fastened by means of clamps 22 (see also Fig. 4). At the lower end of the films weights 24 are attached to hold the films taut.

The catches for the material carriers 7, arranged on the vertical conveyor 5 substantially comprise tube-shaped members 6 which pivot about pins 31 on the chain 5. Their bore 6' is flared at the upper end so that during the upward movement of the one strand of the chain 5 the bent-over part 8 of the material carrier 7 enters easily the bore 6', so that the material carrier 7 together with the film 23 is gripped at the one end and lifted off the horizontal conveyor 12.

A loading station for the material carriers 7 and the films to be developed is provided at the one end of the apparatus. It comprises two inclined guides 15 provided with stops 16 at their lower end. On the upper side of the tank 1, and in particular near its front wall, a shaft 17 is journaled in brackets 25 (Figs. 5-7) which at its bent-over end 17' carries a weight 19 and which is provided with jaws 18 on both sides of the horizontal conveyor chains 12. In front of and parallel to the shaft 17 another shaft 33 is journaled in bearings 32. On both sides of the guides 15 the shaft 33 has levers 20 with bent-over ends, which are pivotably connected to the jaws 18 on the shaft 17 through means of links 21.

Any number of material carriers 7 is placed one after the other on the guides 15. They slide down to the stop 16. For the beginning, the operator has to lift the foremost carrier 7 beyond the stops 16 and place it into the jaws 18. The carrier is thus within reach of the upward moving catch 6 of the transport chain 5; indicated by dotted lines in Fig. 5.

As soon as the catch 6 has received the part 8, the upward movement lifts the carrier 7. In doing so, the jaws 18 are moved upward in clockwise direction into a position 18a, illustrated by dotted lines in Fig. 5, against the action of the weight 19. In this position the carrier 7 leaves the jaws 18 again.

During their upward movement the jaws 18, through means of the links 21, have moved the lever 20 into a position 20a, enabling the lever to lift the next carrier 7 over the stops 16 (position 7a). The weight 19 returns the jaws 18 and the other members into their initial position. The carrier 7, lifted over the stops 16, reaches the horizontal conveyor 12 and is passed into the jaws 18. The catch 6 arriving at the chain 5 then causes operation of the apparatus as described above until all of the material carriers 7 loaded on the guides 15 have been handled.

One after the other, the material carriers 7 with the films are passed down again by the downward moving strand of the chain 5. The films are immersed into the tank until the carrier 7 comes to rest on the horizontal transport chain 12. These retain the carrier and the catch 6 leaves the part 8 of the carrier 7, which is now horizontally moved by the conveyors 12 and the films 23 fastened to the carrier 7 pass through the tank.

At the end of each tank transfer means 17, 18, 19 are mounted, passing each material carrier 7 to the vertical conveyor 5 and lifting the films out of the tank.

After having been moved through the last tank, the developed and washed films are moved by the horizontal conveyor 12 through a door 29 or the like into the chamber 26 for drying. Here, they are placed on the inclined bars 27 where they are retained by stops 28 to be removed through the door 30 of the drying chamber completely developed and dried.

Referring now again to the drawings, Figs. 8 to 13 show an improved embodiment of the catches for the material carriers 7. Furthermore, it is illustrated how to employ more than one vertical conveyor 5. At each point of transfer from one bath to the other, as well as at the front and at the end of the apparatus a vertical conveyor is arranged, formed by an endless chain 45.

The material carriers 7 to which the films 23 are attached by means of clamps 22 (Fig. 9) are moved by the chains 12 of the horizontal conveyor in the direction of the arrow within reach of the upward moving stand of the vertical conveyor 45, in the same manner as described above. Here, they are retained by fixedly mounted stops 78 until the previous carrier 7 and its films has moved away from the vertical conveyor far enough for the next carrier not to touch the previous one. Below the retaining stops 78 double-armed levers 79, 81 are pivotally journaled on a shaft 80, subjected to the action of a spring 82. As will be described later, the double-

armed levers 79, 81 lift the material carrier 7 over the stops 78 to place them within reach of the clamping devices A provided on the vertical conveyor 45.

The chain 45 of the different vertical conveyors which are arranged on the rear side of the tanks pass over sprockets 68 journaled on brackets 67 and are driven either separately or together, from a suitable source (not shown).

According to Figs. 10 to 12 the clamping devices A pivotally mounted on a shaft 53 on the chain comprise a member 50 integral with the plate 49. The member 50 accommodates a slide 52 forced outwardly by a compression spring 51. A flared bore 57 is provided which receives the bent-over part 8 of the carrier 7. The slide 52 subjected to the action of the spring 51 is angled and protrudes into the open passage of the bore 57 so that it grips the part 8 of the carrier 7 when this is in the bore 57 through means of the spring 51. On the other hand, as shown in Fig. 10, the slide 52 extends for a certain length, laterally beyond the bracket 50. On this side, the slide has cone-shaped surfaces cooperating with control members 65 and 66 to be described later.

At the lower end the plate 49 has a recess 76, in which a clamp 55 subjected to the action of a compression spring 56, is journaled on a bolt 44. The clamp 55 has to be transferred into the extreme positions 55', 55'', shown by dotted lines in Fig. 11, its downward extending arms enclosing the conveyor chain 45 from both sides. The clamp 55 prevents the pivoting movement of the plate 49 around the pin 53.

In Figs. 10 and 11 the clamping device A is shown in a position immediately before receiving a material carrier 7. Together with the chain 45 the clamping device is moved in the direction of the arrow. Below the carrier 7, part 8 of which being exactly in the longitudinal axis of the bore 57, the slide 52 abuts against a fixedly mounted control member 65 and is pressed back to completely leave the bore 57. Part 8 of the carrier 7 can easily enter the bore 57 upon further upward movement of the clamping device A and with its horizontal part rest in a groove 58 of the part 50. As soon as the slide 52 leaves the cam 65, its angled portion seizes part 8 of the carrier 7 due to the action of the compression spring 51 so that the carrier is fixedly attached to the vertical conveyor 45.

To subject the clamping device A to a certain resistance when the part 8 enters the bore 57, a bar 47 subjected to the action of a spring 46 is provided above the horizontal conveyor. The carriers 7 are placed beneath this bar 47 immediately before being transferred to the vertical conveyor. When the clamping device moves upwards, the carriers 7 are retained by this bar until the pressure of the spring 46 has been overcome. The bar 47 may move upwards a little and is then returned by the tension spring 46 to its original position. To pass the clamps 55 over the chain 45, or to lift them off the chain, guide means 61, 62, 63, 64 are provided on both sides of the chain 45 so that the clamp 55 is transferred into a position 55' and 55'' only where the direction of movement of the chain 45 is reserved also.

Within reach of the upper sprocket 68 a slide 70 having a slot 77 is journaled on a pivot arm 69 on the bracket 67 to maintain vertical attitude of the films 23 attached to the carrier 7, at the upper point of reservation of the vertical conveyor 45. The clamping device A with its pin 53 enters the slot 77 of the slide 70 in front of the point of reservation, the slide with its lateral arms enclosing the clamping device A also from the sides. Upon further movement of the chain 45 the slide 70 is seized by the clamping device A and transferred from a position shown in Fig. 8 into a position 70'. The arm 69 pivots around an axis 71. It is subjected to the action of a leaf spring 74 which on the one side is fixed to the slide 70 and on the other side is placed between the bolt 72 and the wheel 73. The arm 69 together with the leaf spring

74 forms a double crank, the spring 74 tending to return the slide 70 to its original position as soon as the downward moving strand of the vertical conveyor 45 has removed the clamping device A from the slide. A stop 75 limits the return movement of the slide 70.

When the clamping device A has moved downward far enough its slide 52 comes within reach of the control member 66. The slide abuts against this cam and is again displaced against a spring 51 so that the clamping device in the bore 57 releases the end 8 of the carrier 7. If now the carrier 7 is placed on the horizontal conveyor 12 from above, the clamping device A provided on the vertical conveyor 45, moves out of reach of the carrier 7. The carrier is transferred to the horizontal conveyor 12. At the same time the clamping device A abuts against the control lever 81 (Fig. 13) of the double-armed lever 79, 81.

Against the action of the spring 82 the double-armed lever 79, 81 is moved along and its arm 79 lifts the following carrier 7 over the stop 78 so that the carrier 7 reaches the correct position (below the bar 47) for transfer to the vertical conveyor.

To protect the vertical conveyors and the complete mechanism of the apparatus against splashed liquids from the tanks, a protective wall 85 (Fig. 9) may be provided, covering the vertical conveyors and having slots or the like to allow for the material carrier 7 to extend through the wall 85.

While I have disclosed several embodiments of the present invention, it is to be understood that these embodiments are given by example only and not in a limiting sense, the scope of the present invention being determined by the objects and the claims.

I claim:

1. An apparatus for handling and processing photographic material and developing roll films, comprising a plurality of tanks complementary in number with that of the operations to be performed, separated from each other and individually removable, a loading station for said material to be developed arranged in front of and at the head of the first of said tanks, a delivery station to receive said processed material arranged at the end of the last of said tanks, a plurality of material carriers for the support of said material, a horizontal conveyor disposed in front of and in the rear of said tanks and supporting said material carriers for horizontal movement at a level above said tanks and passing said material through said tanks, a vertical conveyor immersing said material supported by said carriers into each of said tanks and lifting said material carriers from said horizontal conveyor at the end of each run through said tanks, dipping said material again into the next adjacent of said tanks and depositing said material carriers to said horizontal conveyor, said vertical conveyor being mounted solely on the rear side of said tanks in order to provide access for the operator in front of said tanks, catches on said vertical conveyors seizing the rear end of said material carriers while supported by said horizontal conveyor, and means controlling said catches and said material carriers for disengagement of said material carriers from said catches at the front end of each of said tanks causing seizure of said material carriers at the end of the run through each of said tanks to lift the material out of said tanks and said catches for said material carriers comprising a member having a bore flared in the direction of travel and pivotally mounted on said vertical conveyor, and said material carriers comprising a rod bridging said tanks and resting with both of its ends on said horizontal conveyor and each of said material carriers having a bent-down end on the side facing said vertical conveyor and entering said bore of said member.

2. The apparatus, as set forth in claim 1, which includes a drying chamber disposed behind the last one of said tanks and enclosing said delivery station, and said horizontal conveyor extending into said drying chamber.

3. The apparatus, as set forth in claim 1, wherein said vertical conveyor comprises a single endless transport chain having a plurality of upwardly moving strands and a plurality of downwardly moving strands and provided with said catches for said material carriers, and a guide means for said transport chain, said guide means being disposed on the rear side of said tanks in a manner so

that said transport chain is moved upwardly and downwardly, respectively, at the point of transfer from said loading station to the first of said tanks and at the point of transfer from one of said tanks to the next adjacent

5 of said tanks and finally behind the last of said tanks, thereby lifting said material carriers together with said material attached thereto by said upwardly moving strand of said transport chain through means of said catches and lowering and thus immersing said material

10 again into said tanks by said downwardly moving strand.

4. The apparatus, as set forth in claim 1, wherein said vertical conveyor comprises a plurality of different endless chains disposed on the rear side of said tanks, said chains being provided with said catches for said material carriers moving vertically up and down, respectively, at the point of transfer from said loading station to the first of said tanks and at the points of transfer from each of said tanks to the next adjacent of said tanks and behind the last of said tanks.

20 5. An apparatus for handling and processing photographic material and developing roll films, comprising a plurality of tanks complementary in number with that of the operations to be performed, separated from each other and individually removable, a loading station for said material to be developed arranged in front of and at the head of the first of said tanks, a delivery station to receive said processed material arranged at the end of the last of said tanks, a plurality of material carriers for the support of said material, a horizontal conveyor

25 disposed in front of and in the rear of said tanks and supporting said material carriers for horizontal movement at a level above said tanks and passing said material through said tanks, a vertical conveyor immersing said material supported by said carriers into each of said

35 tanks and lifting said material carriers from said horizontal conveyor at the end of each run through said tanks, dipping said material again into the next adjacent of said tanks and depositing said material carriers to said horizontal conveyor, said vertical conveyor being mounted

40 solely on the rear side of said tanks in order to provide access for the operator in front of said tanks, catches on said vertical conveyors seizing the rear end of said material carriers while supported by said horizontal conveyor, and means controlling said catches and said material carriers for disengagement of said material carriers from said catches at the front end of each of said

45 tanks causing seizure of said material carriers at the end of the run through each of said tanks to lift the material out of said tanks and said catches for said material carriers comprising a member having a bore flared in the direction of travel and pivotally mounted on said vertical conveyor, and said material carriers comprising a rod bridging said tanks and resting with both of its ends on said horizontal conveyor and each of said material carriers having a bent-down end on the side facing said vertical conveyor and entering said bore of said member.

50 5. The apparatus, as set forth in claim 5, which includes a clamping device extending into said bore of said member and secured to the latter to retain said bent-down part of said material carrier in said member, and control members fixedly mounted at the point of transfer from said horizontal conveyor to said vertical conveyor to operate said clamping device.

55 6. The apparatus, as set forth in claim 5, which includes clamps pivotally secured to said members and enclosing said transport chain from both sides to prevent said members from pivoting, and fixedly mounted control cams which at the points of reversal of the movement of said transport chain engage and disengage, respectively, the connection between said chain and said member.

60 7. The apparatus, as set forth in claim 5, which includes clamps pivotally secured to said members and enclosing said transport chain from both sides to prevent said members from pivoting, and fixedly mounted control cams which at the points of reversal of the movement of said transport chain engage and disengage, respectively, the connection between said chain and said member.

70 8. The apparatus, as set forth in claim 1, wherein said vertical conveyor comprises a plurality of separate endless chains disposed on the rear side of said tanks and having an upwardly moving strand and a downwardly moving strand, said chains being provided with said catches for

said material carriers and each of said chains moving vertically at the points of transfer from one of said tanks to the next adjacent of said tanks and at the end of the last of said tanks, and transfer means disposed at the upper points of reversal of said chains, said transfer means receiving the incoming catch on said upwardly moving strand of said chain and passing said catch over the point of reversal in its vertical position.

9. An apparatus for handling and processing photographic material and developing roll films, comprising a plurality of tanks complementary in numbers with that of the operations to be performed, separated from each other and individually removable, a loading station for said material to be developed arranged in front of and at the head of the first of said tanks, a delivery station to receive said processed material arranged at the end of the last of said tanks, a plurality of material carriers for the support of said material, a horizontal conveyor disposed in front of and in the rear of said tanks and supporting said material carriers for horizontal movement at a level above said tanks and passing said material through said tanks, a vertical conveyor immersing said material supported by said carriers into each of said tanks and lifting said material carriers from said horizontal conveyor at the end of each run through said tanks, dipping said material again into the next adjacent of said tanks and depositing said material carriers to said horizontal conveyor, said vertical conveyor being mounted solely on the rear side of said tanks in order to provide access for the operator in front of said tanks, catches on said vertical conveyors seizing the rear end of said material carriers while supported by said horizontal conveyor, and means controlling said catches and said material carriers for disengagement of said material carriers from said catches at the front end of each of said tanks causing seizure of said material carriers at the end of the run through each of said tanks to lift the material out of said tanks, said vertical conveyor comprising a plurality of separate endless chains disposed on the rear side of said tanks and having an upwardly moving strand and a downwardly moving strand, said chains being provided with said catches for said material carriers and each of said chains moving vertically at the points of transfer from one of said tanks to the next adjacent of said tanks and at the end of the last of said tanks, and transfer means disposed at the upper points of reversal of said chains, said transfer means receiving the incoming catch on said upwardly moving strand of said chain and passing said catch over the point of reversal in its vertical position, and each of said transfer means comprising a slide receiving said catch and a double crank moving said slide into its initial position after the transfer of each of said catches.

10. The apparatus, as set forth in claim 1, which includes means for retaining said material carriers arriving on said horizontal conveyor and for transferring said material carriers to said catches on said vertical conveyor passing said horizontal conveyor.

11. An apparatus for handling and processing photographic material and developing roll films, comprising a

plurality of tanks complementary in number with that of the operations to be performed, separated from each other and individually removable, a loading station for said material to be developed arranged in front of and at the head of the first of said tanks, a delivery station to receive said processed material arranged at the end of the last of said tanks, a plurality of material carriers for the support of said material, a horizontal conveyor disposed in front of and in the rear of said tanks and supporting said material carriers for horizontal movement at a level above said tanks and passing said material through said tanks, a vertical conveyor immersing said material supported by said carriers into each of said tanks and lifting said material carriers from said horizontal conveyor at the end of each run through said tanks, dipping said material again into the next adjacent of said tanks and depositing said material carriers to said horizontal conveyor, said vertical conveyor being mounted solely on the rear side of said tanks in order to provide access for the operator in front of said tanks, catches on said vertical conveyors seizing the rear end of said material carriers while supported by said horizontal conveyor, and means controlling said catches and said material carriers for disengagement of said material carriers from said catches at the front end of each of said tanks causing seizure of said material carriers at the end of the run through each of said tanks to lift the material out of said tanks, said retaining means comprising pivotable jaws journaled on both sides of said horizontal conveyor, said jaws seizing said material carrier and retaining the latter until received by an upwardly moving catch, and means for returning said jaws into their initial position after each transfer operation.

12. The apparatus, as set forth in claim 1, wherein each of said tanks, each of said vertical conveyors and said horizontal conveyor form self-contained units in order to permit of assembly of any one of a plurality of said units.

13. The apparatus, as set forth in claim 1, which includes a partition wall disposed between said vertical conveyor and said tanks and having slots to allow for said catches for said material carrier to extend through said wall.
